INVENTOR.
B. F. FEHLMAN.

BY

ATTORNEY.

UNITED STATES PATENT OFFICE.

BERNARD F. FEHLMAN, OF MIDWEST, WYOMING, ASSIGNOR OF ONE-HALF TO W. J. CHELEY, OF THERMOPOLIS, WYOMING.

UNDERREAMER.

1,325,148.

Specification of Letters Patent. Patented Dec. 16, 1919.

Application filed November 12, 1918. Serial No. 262,230.

To all whom it may concern:

Be it known that I, BERNARD F. FEHLMAN, a citizen of the United States, residing at Midwest, in the county of Hot Springs and State of Wyoming, have invented certain new and useful Improvements in Underreamers, of which the following is a specification.

This invention relates to boring tools of the class commonly known as under-reamers and used in the construction of deep wells to enlarge the bore thereof beneath an inserted casing which exteriorly is of greater diameter than the bore.

It is the primary object of my invention to provide a tool of the character described which is of simple, strong and durable construction and which includes an arrangement of parts for holding its co-operative bits or cutters, which effectively insures against their disconnection or displacement and permits of their solid and reinforced construction without bolt-holes, key-ways or other weakening passages or recesses which in tools of this type at present in common use, are often the cause of breakage.

The above and other objects all of which will fully appear in the course of the following description I attain by the construction and arrangement of parts shown in the accompanying drawings in which—

Figure 1 is a sectional elevation of my improved under-reamer in its operative position in a well-bore.

Fig. 2, a longitudinal section of the tool taken on the line 2—2, Fig. 1;

Fig. 3, a transverse section taken on the line 3—3, Fig. 1, and

Fig. 4, a perspective view of one of the bits of the tool.

Referring to the drawings, the reference character 2 designates the stock of the tool which for the purpose of assembling the interior working parts of the same, is composed of a body section 3 and a cap-section 4 fastened together by a number of countersunk cap-screws 5.

The body section of the stock is hollowed to provide two recesses 6 of circular section 50 to receive the correspondingly formed knuckles of the bits 13 hereinafter to be described, a longitudinal channel 7 and a therewith continuous chamber 8 for the bar and spring provided to yieldingly hold the

bits in their operative position, and a recess 55 9 the walls 10 of which flare from the first-mentioned recesses to the working end of the stock to provide a space for the movement of the shanks of the bits by which their before-mentioned knuckles are connected with their cutting-heads.

The two sections of the stock have furthermore at opposite ends of its recesses 6, circular seats 12 to receive trunnions formed at the corresponding ends of the knuckles 65 of the bits.

Each bit 13 is formed of a single piece of steel and composed of a cutting head 14 having a rounded cutting edge 15 at its lower end, a knuckle 16 which is rounded to turn 70 within the respective recess 6 of the stock, a shank 17 of reduced width which connects the head with the knuckle, and trunnions 18 which project oppositely from the ends of the knuckle and are fitted in the seats 12 75 at the corresponding ends of the recess in which the knuckle has its movement.

At the juncture of the shank with the head of the bit a shoulder 19 is formed which in the use of the tool abuts against 80 the lower end of the stock as will hereinafter be more fully explained.

The two bits of the tool in their operative position extend divergently with relation to each other as shown in Fig. 1 of the drawings in which position they are capable of moving together under stress against the pressure of a coiled spring 20 which acts upon a headed bar 21 of angular section which is slidingly fitted in the channel 7 90 of the stock.

The outward movement of the bar is limited by engagement of its head with a shoulder between the end of the channel and the therewith continuous enlarged chamber 8 95 which is occupied by the coiled spring 20.

The bar has a tang 22 which extends into the spring to maintain the two parts in their co-operative relation and the end of the bar opposite its head projects into opposite 100 notches 23 in the knuckles of the two bits, which are placed in juxtaposition to each other.

When the bits are in their operative position in which they are yieldingly maintained 105 by pressure of the spring upon the head of the bar whose end extends into the notches of the knuckles, their shanks lie against the

walls 10 of the recess in which they have their movement, and their shoulders 19 abut against the lower end of the stock.

It will thus be seen that the impact of 5 the bits upon the breast of the work is received by the stock and that the more fragile parts of the operating mechanism are relieved from incident shocks and stress.

In the use of my improved tool, the stock 10 carrying the operative parts assembled as shown, is attached to the lower end of the drilling stem by means of the usual taper tool screw joint, in the same manner and occupying the same relative position as the 15 regular drilling bit, the tool thus joined together being suspended from a rope, or drilling cable, by means of which they are lowered into the well bore which in Fig. 1 of the drawing is designated by the reference 20 character A.

After a well is sunk to a considerable depth, its wall is usually secured against caving by the insertion of a tubular casing B.

In order to continue the boring of the 25 well to a greater depth it is necessary to enlarge the bore beneath the casing so as to permit of the latter being driven downwardly and it is for the purpose of producing this enlargement that the reaming tool 30 of the present invention is employed.

Premising that the bore in size equaling the interior diameter of the casing, extends beyond the lower end thereof, the casing is raised about six feet above its resting position 35 at the point in the bore commonly called "the shoulder" at which point the diameter of the bore has been reduced from size of outside diameter to that of the inside diameter of the casing, and the reamer 40 is lowered in the bore to the point of the shoulder, above referred to, after its bits are loosely fastened together by some strands of rope or other easily ruptured fastening means.

45 After the lower end of the stock has reached the position in which the cutting edges of the bits engage the surface of the bore, beneath the casing, the tool is moved up and downwardly and at the same time 50 rotated by means of natural twist of the rope from which it is suspended. At the first blow of the tool against the wall of the bore beneath the casing, the fastening breaks and the heads are caused to separate by the pressure 55 of the spring.

By repeated up and downward motions and rotations of the tool the ground beneath

the casing is reamed as shown in Fig. 1 of the drawings, to a diameter substantially equal to the exterior diameter of the casing, 60 it being understood that the displaced earth is constantly removed from the hole by the means ordinarily employed for this purpose.

It will be readily seen that the solid construction of the bits and the means by which 65 they are pivotally mounted in the stock, secures them against disconnection and displacement and that the chances of their breaking by impact with the breast of the hole upon which they work, are reduced to 70 the minimum by engagement of the shoulders on their heads with the end of the stock, which relieves the knuckles by which they are pivotally held in the stock as well as the bar which yieldingly holds them apart, from 75 the rebound of their cutting action.

Having thus described my invention what I claim and desire to secure by Letters-Patent is:

1. An under-reamer comprising a stock 80 having recesses of circular section and trunnion-seats at opposite ends thereof, outwardly projecting bits having knuckles rotatably fitted in the recesses and trunnions in the respective seats, and spring-pressed 85 means engaging the knuckles to yieldingly maintain the bits in their projecting position.

2. An under-reamer comprising a stock having recesses of circular section, bits having cutting-heads extending outwardly from 90 the stock, knuckles rotatably fitted in the recesses, and shanks connecting the knuckles with the respective heads, in engagement with convergent surfaces of the stock, and spring-pressed means engaging the knuckles 95 to yieldingly maintain the bits in their projecting position.

3. An under-reamer comprising a stock having recesses of circular section, bits having cutting heads extending outwardly from 100 the stock, knuckles rotatably fitted in the recesses, shanks of reduced width, connecting the knuckles with the respective heads, in engagement with convergent surfaces of the stock, and shoulders at the juncture of 105 the shanks with the respective heads, which abut against a superposed part of the stock, and spring-pressed means engaging the knuckles to yieldingly maintain the bits in their projecting position.

In testimony whereof I have affixed my 110 signature.

BERNARD F. FEHLMAN.
